FLOCKED TEXTILE FABRIC

Natalie Leavy, Clifton, N.J., assignor to Decorative Fabrics Company Incorporated, Pawtucket, R.I., a corporation of Rhode Island

Filed Dec. 19, 1960, Ser. No. 63,271

Term of patent 14 years

(Cl. D92—1)

The figure is a plan view of a flocked textile fabric, showing my new design with a portion of the plain fabric being broken away for convenience of illustration.

The design repeats horizontally as indicated.

I claim:

The ornamental design for a flocked textile fabric, as shown and described.
